(57) **CLAIM**

The ornamental design for a vending kiosk, as shown and
described.

DESCRIPTION

FIG. 1 is a front, left side perspective view showing my new
design for the vending kiosk.

FIG. 2 is a front view of thereof.

FIG. 3 is a left side view thereof, the right side thereof being
a mirror image; and,

FIG. 4 is a top view thereof.

The broken lines indicate unclaimed portions and form no
part of the claimed design. The bottom and rear surfaces do
not form part of the claimed design.
